(57) **CLAIM**

The ornamental design for a casing for a watch, as shown and described.

DESCRIPTION

FIG. 1 is a top plan view of a casing for a watch showing my new design;

FIG. 2 is a left side elevational view thereof;

FIG. 3 is a right side elevational view thereof;

FIG. 4 is a first end elevational view thereof;

FIG. 5 is a second end elevational view thereof; and,

FIG. 6 is a bottom plan view.

The broken lines showings are environmental only, and form no part of the claimed design.
